(57) **CLAIM**

The ornamental design for a carrier as shown and described.

DESCRIPTION

FIG. 1 is a perspective view of a carrier showing our new design.

FIG. 2 is a front elevation view of the carrier shown in FIG. 1.

FIG. 3 is a rear elevation view of the carrier shown in FIG. 1.

FIG. 4 is a right elevation view of the carrier shown in FIG. 1.

FIG. 5 is a left elevation view of the carrier shown in FIG. 1.

FIG. 6 is a top plan view of the carrier shown in FIG. 1.

FIG. 7 is a bottom plan view of the carrier shown in FIG. 1.

FIG. 8 is another perspective view of the carrier shown in FIG. 1, with the lid of the carrier shown half open.

FIG. 9 is a cross-sectional view of the carrier shown in FIG. 1, taken along line 9-9 of FIG. 6; and,

FIG. 10 is a cross sectional view of the carrier shown in FIG. 1, taken along line 10-10 of FIG. 6.

The broken lines in FIGS. 1, 6, and 8-10 show portions of the carrier that form no part of the claimed design.

1 Claim, 5 Drawing Sheets
